UNITED STATES PATENT OFFICE.

MICHAEL McMAHON, OF TOLEDO, OHIO.

PRINTING APPARATUS.

No. 872,302.

Specification of Letters Patent.

Patented Nov. 26, 1907.

Application filed February 4, 1907. Serial No. 355,591.

To all whom it may concern:

Be it known that I, MICHAEL McMAHON, a citizen of the United States, and a resident of Toledo, in the county of Lucas and State 5 of Ohio, have invented a certain new and useful Printing Apparatus; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to printing apparatus of the class particularly designed for the printing of cloth, paper, bags, paper or wooden box covers, or the like; and has for its object the provision of a machine of 20 this class, which is small, simple and of economical construction and intended more particularly for the use of merchants to enable them to stamp their business cards or other desired matter on the paper bags or covers 25 of boxes employed in their business.

The operation, construction, and arrangement of the parts of the invention are fully described in the following specification and illustrated in the accompanying drawings, in 30 which,—

Figure 1 is a front elevation of the apparatus embodying the invention with the hood removed. Fig. 2 is a vertical transverse section on the line $x-x$ in Fig. 1. Fig. 35 3 is a section of the upper portion of the frame with the adjustable bearing-plate swung in inoperative position, and Fig. 4 is a top plan view of one of the platen-roll supports.

40 Referring to the drawings, 1 1 designate spaced standards or uprights, which have their upper ends connected by a horizontal member 2 and their lower ends secured to a base member 3 or other suitable object.

45 Suspended from the connecting member 2 of the frame by bolts 4, or in any other suitable manner, is an inverted U-shape frame 5, the pendent arms of which constitute bearing-brackets for the coacting type-roll 6 and 50 inking-cylinder 7, and for this purpose are provided with the angled bearing slots 8 for removably receiving the trunnions of the inking-cylinder and with the axially alining bearing-apertures 9 for receiving the shaft 10 55 to which the type-roll 6 is secured by pins

10^a. The ends of the shaft 10 are preferably extended beyond the bearing-arms 5 and suitably journaled in the contiguous frame standards 1 1, and one end is provided without its standard with a crank-arm 11 to 60 facilitate a turning thereof. The type-roll 6 has the die-plate 12 secured to one side thereof and its opposite side cut away as at 13, to form a cam-shaped roll, substantially 65 as shown.

Rising from the base 3 beneath the type-roll 6 are the two upright or vertical arms 14 14, which have their upper ends turned outwardly to form shelves 15 and slotted, as 70 at 16, to permit the trunnions of a platen or impression-roll 17 to be removably dropped therein, said roll being supported in suitable position for its circumference to contact with the die-plate 12 of the roll 6 when the latter 75 is revolved. In order to provide a yielding bearing for the platen-roll 17 its trunnions are supported by slotted bearing-blocks 18, which are slidingly carried by bolts or pins 19 beneath the shelves 15 of the uprights 14, and are normally retained in yielding contact 80 with said shelves by the action of the coiled compression-springs 20, which are supported below the blocks 18 by a follower-plate 21, also carried by the bolts or pins 19. The tension of each set of springs 20 is regu- 85 lated by an adjusting-screw 22, which is centrally threaded through a plate 23 carried at the lower ends of the associated bolts or pins 19, and has its upper or inner end centrally abutting the under side of the follower-plate 90 21, so that a turning of the screw will effect a raising or lowering of the plate 21 as the thickness of the work to be printed and the impression to be given may require.

24 designates a bearing-plate which is adjustably secured to the outer side of each pendent arm of the bearing frame 5 by a bolt 25 passing through an aperture in the arm and longitudinal slot 26 in the plate and carrying a winged nut at its outer end. This 100 plate has its upper end slotted and one side of the slot partially cut away, as at 27, to register with the angled slot 8 of the arm, and its lower end slotted, as at 28, to adapt it to freely straddle the shaft 10, as shown in Fig. 105 2.

2. The purpose of this plate is to compensate for any wear which may take place in the associated bearing-apertures 9 of the pendent arm, as the plate can be adjusted vertically to take up the wear, thus prevent- 110

ing a jumping of the type-roll as it has contact with the impression-cylinder when turned.

5 A hood 29 is shown as being suspended from the frame member 2 for protecting the inking-cylinder and type-roll, and has one side hinged, as at 30, to facilitate the removal of said cylinder and roll.

10 The operation of the apparatus is as follows:—After the tension of the springs 20 has been adjusted to suit the nature of the work and the impression desired, the article to be printed, whether it be a sheet of paper, a paper-bag, a wooden or a paste-board box-15 cover, is placed on the upper surface of the impression-roll 17 within the opening formed between it and the type-roll by the cutaway portion 13 of the latter. This being done the crank-arm 11 is given a turn and the 20 type-roll thereby caused to revolve so that the die-plate 12 thereon, which is inked by the inking cylinder 7, comes in contact with the work and leaves the desired impression thereon. During the printing the operator 25 may either retain hold of the article and withdraw it from the same side of the apparatus in which it is fed as soon as the type-roll has revolved sufficiently to release it, or it may be permitted to pass through and be 30 taken from the opposite side of the apparatus. Should it be desired to stamp the covers of paste-board boxes or other articles having a depending marginal flange, an impression-roll of suitable width for its impression 35 surface to fit within the cover or other article between the side flanges thereof is employed.

Having thus described my invention, what I claim as new, and desire to secure by Letters Patent, is,—

40 1. In a printing apparatus, a pair of upright members having their upper ends each formed with a lateral projection and longitudinally slotted, bearing members yieldingly carried by said projections, means for adjusting the yieldability of said bearing-members, and an impression-roll supported by said bearings, and a type-roll for coacting with the impression-roll.

45 2. In combination an inverted U-shaped standard, arms pendently secured to the loop portion of the standard and provided with two sets of bearings, an inking-roll mounted in one of said sets of bearings and a type-50 cylinder in the other of said sets, said cylinder having one side partially cut away,

means for revolving the type cylinder, upright bearing standards disposed intermediate the legs of the main standard, and an impression roll yieldingly mounted in said upright standards beneath the type-cylinder.

55 3. In combination, a base, an inverted U-shaped standard rising from the base, bearing arms pendently carried by the loop of the standard, a shaft journaled in said arms and the legs of the standard, a crank carried by said shaft, a type-cylinder mounted on the shaft between said arms, an inking-roll journaled in the arms above the type-cylinder, bearing-arms rising from the base intermediate the legs of the standard and having their upper ends turned outwardly to form shelves, bearings yieldingly suspended from said shelves, and an impression-roll journaled in said bearings, substantially as described.

60 4. In combination, a base, a bearing frame rising from the base, an inking-roll and a type-cylinder journaled in said frame, means for rotating the cylinder, arms rising from the base beneath the bearing-frame and having their upper end portions longitudinally slotted and bent outwardly at a point intermediate the ends of the slots, bearings yieldingly carried at the under sides of the outwardly turned portions of the arms, and an impression-roll having its trunnions supported by said bearings and permitted to be freely raised therefrom through the slots in the arms.

65 5. The combination with the type-cylinder, of subjacent bearing-standards having their upper end portions longitudinally slotted and bent outwardly at points intermediate the ends of the slots to form shelves, pins pendently carried by said shelves, spring 95 20 and plates 21 and 23 carried by said pins, bearing-blocks yieldingly supported beneath said shelves by the springs 20, adjusting-screws threaded to the plates 23 and coacting with the plates 21 to adjust the tension of the springs, and an impression-roll having its trunnions projecting through the slots in the standards and mounted in the bearing-blocks, substantially as described.

70 In testimony whereof I have hereunto signed my name to this specification in the presence of two subscribing witnesses.

MICHAEL McMAHON.
